CLAIM

I claim the ornamental design for a sheath for resistance band, as shown and described.

DESCRIPTION

FIG. 1 is a front perspective view of the sheath for resistance band showing my new design;

FIG. 2 is a front view thereof;

FIG. 3 is a back view thereof;

FIG. 4 is a left side elevation view thereof;

FIG. 5 is a right side elevation view thereof;

FIG. 6 is a top plan view thereof; and,

FIG. 7 is a bottom plan view thereof.

The broken line showing of portions of the sheath for resistance band depicts environment and forms no part of the claim.
